(57) **CLAIM**

The ornamental design for a one piece security tag, as shown and described.

DESCRIPTION

FIG. 1 is a perspective view taken from the front, left and top sides showing the new design;

FIG. 2 is a perspective view taken from the rear, right and top sides;

FIG. 3 is a left side view of the design, shown in an alternate position, the right-side view being a mirror image thereof; FIG. 4 is a left side view of the design shown in the same position as FIG. 1;

FIG. 5 is a top plan view of the design thereof;

FIG. 6 is a bottom plan view thereof;

FIG. 7 is a front-end view of the design shown in the alternate position as per FIG. 3; and

FIG. 8 is a rear end view of the design and configuration shown in FIG. 1 thereof.
